(57) **CLAIM**

The ornamental design for an artificial tree base assembly, as shown and described.

DESCRIPTION

FIG. 1 is a perspective view of an artificial tree base assembly, showing our new design;

FIG. 2 is a bottom plan view of the base assembly of FIG. 1;

FIG. 3 is a top plan view of the base assembly of FIG. 1; FIG. 4 is a top perspective view of the downwards-facing notched connector structure of FIG. 1, shown separately for ease of illustration;

FIG. 5 is a top perspective view of the upwards-facing notched connector structure of FIG. 1, shown separately for ease of illustration;

FIG. 6 is a front view of the downwards-facing notched connector structure of FIG. 4;

FIG. 7 is a side view of the downwards-facing notched connector structure of FIG. 4 rotated so two notches are visible;

FIG. 8 is a side view of the downwards-facing notched connector structure of FIG. 4, rotated so a single notch is in a first visible position;

FIG. 9 is a side view of the downwards-facing notched connector structure of FIG. 4, rotated so a single notch is in a second visible position;

FIG. 10 is a top plan view of the notched connector structure of FIG. 4 rotated into a third position; and,

FIG. 11 is a top plan view of the notched connector structure of FIG. 5 rotated into a fourth position.

The broken lines showing the environment are for illustrative purposes only and forms no part of the claimed design.
